United States Patent Office

Des. 181,265
Patented Oct. 29, 1957

181,265

SQUEEZE TOY

Robert Y. Allen and Melvin Shaw, Los Angeles, Calif.,
assignors to Tinkle Toy Company, Inc., Youngstown,
Ohio, a corporation of Ohio

Application February 18, 1957, Serial No. 44,891

Term of patent 3½ years

(Cl. D34—2)

Figure 1 is a perspective view of the front and one side of the squeeze toy, showing our new design;

Figure 2 is a perspective view of the back and other side thereof; and

The bottom is substantially plain.

We claim:

The ornamental design for a squeeze toy, as shown and described.
